CANOPY FOR CHILDREN'S PLAY DEVICES

Benjamin H. Kennedy, Rochester, N. Y.

Application November 16, 1935, Serial No. 50,125

8 Claims.

(Cl. 135—5)

This invention relates to canopies and while not necessarily restricted to such use, the same is primarily designed as a sun shade for children's play devices or pens, sand boxes and the like.

5 The invention broadly comprehends a canopy including a flexible top and a supporting structure therefor adapted to be removably associated with a play pen or similar device.

The invention further resides in a canopy of 10 the indicated character which includes a knock-down supporting structure so constructed and arranged as to permit of the ready setting up and assembly of the same with the canopy top and the play device, and the removal and disassembly 15 thereof for collapsing into a compact arrangement for storage and shipment.

More specifically the invention provides a canopy of the character set forth and for the purpose specified in which the supporting structure 20 consists of a pair of side frames each including pivotally connected resilient cross arms having means engageable with the play device for mounting said side frames thereon so as to bind and limit the pivotal movement of the frame arms and 25 stretcher elements detachably engageable with the upper ends of the frame arms and removably associated with the canopy top so as to support the same in a taut condition.

The invention further includes means carried 30 by the side frames and engageable with the play device for securing the canopy in associated relation therewith and for tensioning and retaining the frame arms so as to render the structure rigid when in applied position.

35 The invention further embodies in a canopy of the type specified, a side curtain including means for connecting the lower edge to the play device.

Other objects of the invention reside in the provision of a canopy of this character which 40 embodies but few and simple parts capable of economical production and which is highly efficient for its intended purpose.

With the above enumerated and other more detailed objects in view, reference is now made to 45 the following specification and accompanying drawing in which there is set forth a preferred embodiment of the invention, while the claims cover other modifications which fall within their scope.

50 In the drawing:

Fig. 1 is a fragmentary perspective view of a canopy constructed in accordance with the invention illustrating the same in set up applied position on a play device.

55 Fig. 2 is a fragmentary sectional plan view

taken approximately on the line indicated at 2—2 in Fig. 1.

Fig. 3 is a perspective view of one of the side frames in partially collapsed condition.

Fig. 4 is a fragmentary perspective view of one 5 of the stretcher elements.

Referring to the drawing by characters of reference, the canopy includes a top 5 of flexible material such as canvas, duck or the like and which is of a size and shape conforming generally 10 to the top plan configuration of the play device or pen A. At two of its opposite marginal edges, the top 5 is formed with tunnels 6 and 7 which may be formed by turning over and hemming the edge 8 thereof and by applying thereto a separate strip 9. The separate strip 9 is usually employed where it is desired to provide a side curtain 10 as a continuation of the top 5.

The supporting structure for the canopy top 5 consists of side frames designated generally by 20 the reference character 11 and each of which includes a pair of cross arms 12 and 13 pivotally connected as at 14 intermediate the ends so that the same may be swung from a substantially aligned collapsed position to an open supporting 25 position. The lower ends of the arms 12 and 13 are respectively provided with inwardly offset hooked terminals 15 and 16 which are disposed in a plane perpendicular to the plane of the side frame, whereby said terminals engage over the 30 upper rail or edge B of a side of the play device adjacent the juncture of said side with the adjoining sides respectively to abut with and bind against said adjoining sides in order to limit the spreading of the lower ends when the frames are 35 applied to the play device. The upper ends of the arms 12 and 13 are respectively provided with inwardly directed extremities 17 and 18.

The supporting structure further includes a pair of stretcher rods 19 which are of a length 40 equal to the length of the canopy top 5 and which are adapted to be inserted respectively in the tunnels 6 and 7 thereof to render the opposite side edges of the top rigid longitudinally when in applied relation thereto. The opposite 45 ends of the stretcher rods 19 are formed with sockets 20 for the reception of the extremities 17 and 18 of the side frame arms 12 and 13, which extremities are inserted in the sockets after the stretcher rods have been emplaced in the tunnels. 50

In order to provide means for securing the canopy in place on the play device and to stretch and retain the top in a taut condition, each of the side arms 11 is provided with a lashing strap 21 which is anchored thereto at the pivotal con- 55

nection 14 and which is designed to be looped about the side upper rail B of the play device and retained in place by means of any suitable form of buckle 22. Due to the fact that the side arms 5 12 and 13 are of a resilient nature, the tightening of the lashing straps 21 will cause the side arms to buckle slightly thereby spreading the terminals 17 and 18 and the stretcher rods 19, as shown in full lines in Fig. 1 of the drawing.

10 In order to secure the side curtain in a stretched vertical condition, the same is preferably provided with lashing straps 23 which are looped about the upper rails B and secured in adjusted position by any suitable form of 15 buckling 24.

When not in use, it is obvious that the arms 12 and 13 of the side arms 11 may be collapsed to a folded substantially parallel position and the side frames, together with the stretcher rods 20 19, may be rolled in the top and curtain to a compact arrangement for storage and shipment.

What is claimed is:

1. A canopy for a child's play pen including a 25 pair of stretcher rods removably associated with opposite side edges of a flexible top and a pair of supporting frames each including a pair of pivotally connected crossed arms detachably connected with opposite ends of the stretcher rods, and means on the lower end of each of said 30 arms for embracingly engaging the upper edge of a side of the play pen.

2. A canopy for a child's play pen including a 35 pair of stretcher rods removably associated with opposite side edges of a flexible top and a pair of supporting frames each including a pair of pivotally connected crossed arms detachably connected with opposite ends of the stretcher rods, means on the lower end of each of said arms for embracingly engaging the upper edge of a side 40 of the play pen, the means at the lower ends of the side arms of each supporting frame being adapted to abut with opposing sides of the play pen and lashing means connected with each frame at the point of pivotal connection of the arms 45 for engaging with a side of the play pen to secure the canopy thereto and for exerting a pull on the frame to spread the upper ends of the arms so as to render the top taut.

3. A canopy for a child's play pen including 50 a pair of stretcher rods removably associated with opposite side edges of a flexible top, and a pair of supporting frames each including a pair of pivotally connected crossed resilient arms detachably connected with opposite ends of the stretcher rods, means on the lower end of each of said 55 arms for embracingly engaging the upper edge of a side of the play pen, the means at the lower ends of the side arms of each supporting frame being adapted to abut with opposing sides of the 60 play pen and lashing means connected with each frame at the point of pivotal connection of the arms for engaging with a side of the play pen to secure the canopy thereto and for exerting a pull on the frame to spread the upper ends of the arms 65 so as to render the top taut.

4. A canopy for a child's play pen including a pair of stretcher rods removably associated with opposite side edges of a flexible top and a pair of supporting frames each including a pair of pivotally connected crossed resilient arms detachably 5 connected with opposite ends of the stretcher rods, and means on the lower end of each of said arms for embracingly engaging the upper edge of a side of the play pen, the means at the lower ends of the side arms of each supporting frame 10 being adapted to abut with opposing sides of the play pen and lashing means connected with each frame at the point of pivotal connection of the arms for engaging with a side of the play pen 15 to secure the canopy thereto and for tensioning the frames so as to produce a bowing of the same and thereby spread the upper ends of the arms to render the top taut.

5. A canopy for a child's play pen including a 20 pair of stretcher rods removably associated with opposite side edges of a flexible top and a pair of supporting frames each including a pair of pivotally connected crossed arms respectively detachably connected with opposite ends of the stretcher rods and having inwardly directed 25 hooked lower ends for embracingly engaging the upper edges of the sides of the play pen.

6. In a canopy for a child's play device, a supporting structure for a flexible top comprising longitudinal stretcher rods located on opposite 30 sides of the top and a pair of oppositely disposed side frames between the upper ends of which the stretcher rods are removably supported, each of said side frames having at the lower end thereof means engageable with the play device for 35 mounting the frame thereon.

7. In a canopy for a child's play device, a supporting structure for a flexible top comprising longitudinal stretcher rods located on opposite 40 sides of the top and a pair of oppositely disposed side frames between the upper ends of which the stretcher rods are removably supported, each of said side frames having at the lower end thereof means engageable with the play device for 45 mounting the frame thereon, and means engageable with the side frames and with the play device for securing the canopy in associated relation therewith and for tensioning the side frames to render the top taut.

8. In a canopy for a child's play device, a supporting structure for a flexible top comprising longitudinal stretcher rods located on opposite sides of the top and a pair of oppositely disposed side frames by the upper ends of which 55 the stretcher rods are supported, each of said side frames having at the lower end thereof means engageable with the play device for mounting the frame thereon, and means engageable with the side frames and with the play device 60 for securing the canopy in associated relation therewith and for tensioning the side frames to render the top taut.
